UNITED STATES PATENT OFFICE.

CHARLES J. JOHNSON, OF ST. LOUIS, MISSOURI, ASSIGNOR OF ONE-THIRD
TO FREDERICK HORN, OF ST. LOUIS, MISSOURI.

REGULATOR FOR GAS-JETS.

No. 881,512.

Specification of Letters Patent.

Patented Sept. 18, 1906.

Application filed February 5, 1906. Serial No. 299,554.

To all whom it may concern:

Be it known that I, CHARLES J. JOHNSON, a citizen of the United States, residing at the city of St. Louis, State of Missouri, have invented a certain new and useful Improvement 5 in Regulators for Gas-Jets, of which the following is a specification.

My invention relates to that form of gas-jet which is particularly useful on Bunsen burners, and where it is necessary to introduce a jet for mixture with air which can be regulated as to size.

Various devices have heretofore been employed, but which either depend on artificial 15 pressure or which cut the jet into numerous subjects, all of which fail to accomplish the best results. My device furnishes a solid cylindrical stream of gas, the size of which may be regulated as desired and from which 20 maximum results can be obtained.

Referring to the accompanying drawings, which form a part of the specification, Figure I shows a vertical section of the entire device. Fig. II shows a detail view, part in vertical 25 section, of the gas-tube. Fig. III shows an elevation of the device, showing maximum capacity. Fig. IV is similar to Fig. III, but showing a minimum capacity.

1 is the tube through which gas is introduced. 2 is the conical-shaped end thereof, where ignition takes place.

3 is the surrounding protection, furnished with perforations 4, through which air is supplied.

35 5 is a plug screwed into an elbow of the tube 1, which protects an opening through which a bar 6 is inserted and which may be

raised or lowered by a set-screw or key 7. The upper end of this is flared and cut with slits 8. The flaring shape retreats at the end 40 9 and is capable of compression, so that when bar 6 is screwed upward the flanges close, as shown in Fig. IV, yet which leave a central orifice exactly round, allowing the exit of a circular jet of gas. Even though compressed 45 to the minimum the flaring shape of the end of bar 6, furnished with slits, allows gas to escape, as shown in Fig. II. It may, however, be constructed so that it will be entirely closed. The gas is controlled by the usual 50 stop-cock. (Not shown.) The retreating ends 9 of the regulator fit snugly in the inside of the cone 2, so that the jet, whether large, Fig. III, or small, Fig. IV, is relatively always 55 the same and enters the ignition-chambers at the exact center. There is no danger of its becoming clogged, as the flaring construction with slits 8 always provides more space than the size of the jet.

What I claim as new, and desire to secure 60 by Letters Patent, is—

In a regulator for gas-jets, the combination of a tube provided with a conical end, said end having a round opening; a regulator having a round orifice seating within said end 65 and provided with longitudinal openings, which openings are broader midway their length than at their ends; and a means of raising or lowering said regulator in reference to said tube; substantially as described.

CHARLES J. JOHNSON.
